HAIR WAVING PAD AND METHOD

Bernard A. Sterling, Chicago, Ill.

Application April 19, 1937, Serial No. 137,600

3 Claims. (Cl. 132—36.2)

This invention relates to the waving of hair upon the human head, and more particularly to the production of lasting waves such as are known as "permanent" waves.

Heretofore, it has been the practice in producing waves of this sort to divide the hair into strands or locks, to grip the strands adjacent the scalp with clamps, to wind the strands of hair upon curlers or waving devices up to positions adjacent the clamps, to mount the curlers or waving devices with the hair thereon on the clamps, and to apply suitable pads and heat to the hair while the same is in place on the curlers for the purpose of producing the desired set in the waves.

Electric heaters have been commonly employed, but the present practice is to employ pads containing a chemical or chemicals which upon wetting will develop the desired heat without electric or other additional heating devices.

Where pads of the sort last mentioned are used, they are applied to the hair while the same is in place on the curlers and separate clamps have been employed for clamping the pads upon the hair while the same is in position upon the curlers, these clamps being relatively heavy and depending upon the presence of the curlers within the waved hair to hold them in place.

One of the main objects of the present invention is to provide a hair-waving pad of the class described having, in combination, a pad part and fastening means carried by and constituting a unitary part of the pad for securing the pad upon the hair.

The pad of the present invention eliminates the use of separate clamps and the like for clamping the pad upon the hair. This reduces the cost, simplifies the waving operation, and avoids the weight and other discomfort of such additional clamps and the like.

While the pad is particularly adapted for home use and for application to the hair after the same has been wound upon and removed from the curling or waving device, it is to be understood that the pad is not limited to such use but may be employed in beauty shops and elsewhere as suitable or desired, and it may be applied to the hair after the same has been wound on the curling or waving device and while it is still in place on such device.

It is also an object of the invention to provide an improved method of producing a lasting wave which comprises winding a strand or lock of hair upon a curler or waving device to form the desired curl or wave, removing the curled

lock from the curler, and thereafter covering the curled lock of hair and applying heat to set the curl, and, more specifically, thereafter applying around the curled lock of hair chemical means which will develop heat upon wetting, and a heat insulating pad around said curled lock of hair and chemical means, and clamping the same upon the hair until the wave is set.

Further objects and advantages of the invention will appear from the following detailed description taken in connection with the accompanying drawing, in which:

Figure 1 is a fragmentary perspective view showing the hair divided into a strand or lock, and the manner of applying the protector pad thereto;

Figure 2 is a similar view after winding the lock of hair into the desired curl or wave and removing it from the curling or waving device;

Figure 3 is a view similar to Figures 1 and 2 showing a pad embodying the present invention applied to the curled or waved lock of hair;

Figure 4 is a top plan view of the pad;

Figure 5 is a bottom plan view of the pad; and

Figure 6 is a fragmentary section taken on the line 6—6 of Figure 4.

Referring now to the accompanying drawing, the first step in waving the hair 5 on the human head 6 is to divide the hair into a lock or strand 7.

A suitable protector 8 is placed over the strand 7 and up adjacent the scalp to protect the same from the heat of the waving operation. The illustrated protector 8 comprises a heat insulating pad or felt or other suitable material having a slit at 9 through which the strand of hair is passed, as shown in Figure 1. The protector 8 may, of course, be a clamp protector with pivotally connected jaws, or any other suitable or preferred form of protector may be employed.

The next step is to wind the strand of hair 5 upon a suitable curler or waving device (not shown) to form the desired curl or wave indicated at 10 in Figure 2. The curler or waving device may be of the type shown in my copending application Serial No. 105,862, filed October 16, 1936, wherein a hairpin 12 for holding the hair in its curled form is applied to the curled lock of hair 10 by removal of the same from the curling device. The lock or strand of hair may, of course, be curled or waved upon other forms of curling devices, or in any other suitable or preferred manner within the scope of the appended claims.

The curl 10, upon completion, has the pin 12

90

40

45

50

55

applied to hold the same in curled form, and the curl as thus formed and held is disposed adjacent the protector 8. As shown in Figure 2, the curling or waving device has been removed from 5 the curl 10.

The waving pad is indicated in its entirety at 15 and comprises a flat envelope 16 containing copper chloride, talc and aluminum, or other suitable chemical means at 17, which will develop 10 heat upon wetting with water. The use of such chemical means in hair waving pads for the purpose set forth is well known in the art, and such means therefore will not be further described in detail here.

15 The envelope 16 is formed of tin or other metal foil, with perforations in its outer side as indicated at 18. A water absorbent fabric 19 covers the side of the envelope 16 provided with the perforations 18, and the marginal edges of the 20 metal foil envelope are folded over the marginal edges of the fabric covering 19 as indicated at 20. A heat insulating pad 21, formed of felt, flannel, or other suitable material, covers the back of the envelope 16, and the margins of this pad 21 preferably extend beyond the margins of the envelope 25 16. The envelope 16 may be formed of waxed paper or other suitable material instead of metal foil, and the pad 21 provides protection against the heat developed within the pad upon wetting 30 of the chemical means at 17 and for holding such heat in and upon the curl 10 upon application of the pad thereto.

35 The fastener means carried by and constituting a unitary part of the pad 15, for securing the pad around the curl 10, comprises a generally U-shaped pliable wire 25, with its base 26 disposed between the pad 21 and the back of the envelope 16. The ends or legs of the generally 40 U-shaped wire project at 27 from one margin 28 of the pad, and are adapted to be bent over the opposite margin 29 when the pad is wrapped around the hair as shown in Figure 3 to hold the 45 pad in place upon the hair.

Wire staples 30, applied by the usual stapling 45 devices now in common use, secure the envelope 16, absorbent fabric covering 19 and pad 21 together, and in the illustrated embodiment of the invention the two left hand staples 30, as viewed in Figure 4, are applied over the legs of the wire 50 fastener 25 to secure the same to the pad. The parts may be stitched together and the fastener device secured thereto by stitching, or in any other preferred manner within the scope of the broader aspects of the present invention.

55 In operation, the hair is divided into the strand 7, which is passed through the slit 9 in the protector 8, and the protector is positioned as shown in Figures 1 to 3. The strand of hair is then curled or waved as herein set forth, into the 60 form of the curl 10 with the pin 12 applied thereto. The pad 15 is then wrapped around the curl 10, with the water absorbent fabric 19 and the apertures 18 of the envelope 16 presented toward the curl, and the pad 21 covering the same 65 for protection against the heat and to hold the heat in and around the curl 10.

70 The margin 28 of the pad is now in close proximity to the opposite margin 29, and the projecting prongs 27 are bent over this opposite margin 29 to hold the pad in place upon the hair until the curl is set. When the chemical means at 17 is wetted it provides the heat necessary to form the desired wave.

Where I refer to the wire 27 as being pliable, I intend to convey by such expression the meaning that this wire is capable of being bent into engagement with the opposite margin of the pad as shown in Figure 3, and, when so bent, remains engaged until the projecting prongs are bent out of engagement with the margin 29 of the pad. The particular wire 27 employed in the illustrated embodiment of the invention is fabric covered, as indicated at 35 in Figures 4 and 6. The pad is 10 thus clamped firmly around the curled or waved hair without separate clamping devices, and, as illustrated, it is applied to the curl 10 after removal of the same from the curling or waving device, although it is to be understood that the 15 pad may be applied to the hair after the same has been wound on the curling or waving device and while it is still in place on such device, within the scope of the appended claims.

The present invention eliminates the use of 20 separate clamping devices and the like, and is adapted for use around the curled or waved hair after removal of the same from the curler, because it does not depend upon the presence of the curler within the waved hair to hold it in place. 25 The pad is adapted for home use, or for use in beauty parlors or elsewhere as desired, and, as already set forth, it may be applied either after the curl is removed from the curler or while the curl is still in position upon the curler. 30

I do not intend to be limited to the precise details shown or described.

I claim:

1. In a hair waving pad of the class described, in combination, a pad part, and fastening means 35 carried by and constituting a unitary part of said pad for clamping said pad upon the hair, said fastening means comprising prong means secured to the pad and projecting from one margin thereof, said prong means being adapted to be 40 bent over the opposite margin of the pad when the pad is wrapped around the hair and to remain in bent position to hold the pad in place upon the hair.

2. In a hair waving pad of the class described, 45 in combination, a pad part, and a generally U-shaped pliable wire secured to said pad part with its ends projecting from one margin of said pad and adapted to be bent over the opposite margin of the pad when the pad is wrapped 50 around the hair to hold the pad in place upon the hair.

3. In a hair waving pad of the class described, in combination, a generally flat envelope containing chemical means which will develop heat 55 on wetting, said envelope having perforations in the side presented toward the hair, a water absorbent fabric covering the perforated side of said envelope, a felt-like pad covering the opposite side of said envelope and secured thereto, the margins of said felt-like pad extending beyond the margins of said envelope, and a generally U-shaped pliable wire secured to said pad with its base disposed between the felt-like pad and the back of the envelope, said wire having its 60 ends projecting from one margin of the pad and adapted to be bent over the opposite margin of the pad when the pad is wrapped around the hair to hold the pad in place upon the hair. 65

BERNARD A. STERLING.
